UNITED STATES PATENT OFFICE

ROBERT N. HARTZELL, OF PIQUA, OHIO, ASSIGNOR TO HARTZELL INDUSTRIES, INC., OF PIQUA, OHIO, A CORPORATION OF OHIO

VENEER MACHINE

Original application filed January 26, 1931, Serial No. 511,238. Divided and this application filed December 18, 1931. Serial No. 581,900.

This invention relates to improvements in machines for cutting or forming veneer, and has for its object to provide a machine in which there is a stationary knife to which one end of a log or a veneer piece is applied in such a manner that a strip of veneer is cut from the end of the log.

It is particularly the object of this invention to provide, in connection with a veneer machine, a cone-shaped knife which is adapted to support one end of a work piece or log from which the veneer is cut, while there is also provided, in connection with the cutter, means for supporting the other end of the log and causing it to rotate and gyrate around the axis of the cone-shaped cutter.

It is a further object of this invention to provide means for rotating and gyrating one end of a log about the cutter and removing the veneer strip from the work from the same source of power that rotates the log or work.

These and other advantages will appear from the following description taken in connection with the drawing.

Referring to the drawing:

Figure 1 is a section on the line 1—1 of Figure 2.

Figure 2 is a vertical, longitudinal section through Figure 1.

Figure 3 is a top plan view of the apparatus.

In order to provide supports for the apparatus or veneer forming mechanism there is provided a plurality of standards 1, 2, 3 and 4, which form a supporting frame. On this frame, near the bottom, is a platform 5 which has thereon a bearing 6. Resting on this bearing is a collar 7, which supports a gear 8 adapted to rotate on the bearing in a horizontal position.

Immediately above the gear is a carrier 9, which receives the strips of veneer as they are cut from the work or log. This carrier is supported above the gear by means of a friction plate or clutch 10 and rotates thereby with the gear. Meshing with the gear is a pinion 11 located on a vertical shaft 12 supported on the platform 5 and by a frame 16, later to be described. Continuous with the shaft 12 is an armature shaft 13 on a motor

14. This armature shaft has a pinion 15 which meshes with a gear 17.

The frame 16 is supported by the standards above the platform 5 and is used for supporting the motor, the transmission parts such as the gear 17, a shaft 40 and a cutter 18. This cutter is located intermediate the standards and is supported by the frame 16. It is conical in shape, with a slot in one side and a knife or cutter adjacent the slot. The cutter is supported by means of flanges 19 on the frame 16. The slot in the cutter is indicated by the numeral 20.

On one side of the slot is a guide bar 21, while on the other side and extending into the slot is a knife 22 for cutting veneer from a log supported in and by the cone-shaped cutter. The cutter is vertically disposed and has an axis 23 which extends vertically upwardly from the cutter. Supported by the cutter is a work piece 24. In the present instance this work is a log or pole from which veneer strips are to be cut. One end of the log or work piece is suitably shaped and inserted in the cone-shaped cutter, and is supported thereby in an inclined position; that is, the log is inclined to the vertical and also at an angle to the sides of the cone-shaped knife or cutter.

By this means as the log or work piece rotates and gyrates a strip is cut from the end extending into the cutter so that by four rotations of the wood piece a complete strip of veneer, substantially square, is cut having thereon four symmetrically arranged groups of wood grains, as shown and described in my copending application, of which this is a division, Ser. No. 511,238, filed January 26, 1931.

The axis of the work is indicated by the numeral 25 and is supported at its upper end by means of a cap member 26, as shown in Figure 2. On each of the standards 1, 2, 3 and 4 is a trackway 27, adapted to guide a carriage 28, which has on each end a roller 29 so that the carriage may easily move up and down in the trackway. There are four of these carriages, one for each standard and trackway.

Attached to the carriages by means of suit- 169

able arms is a crosshead 30, on which is a weight 31 tending to force the crosshead and carriages downwardly, and force the log or work piece into the cone-shaped cutter. Located centrally in the crosshead is a spindle 32 in line with the axis of the cone-shaped cutter. This spindle is fixed and has fixed thereto a gear 33, the axis of which is in line with the axis 23 of the cutter.

Supported by the spindle for rotation around it is a gear case 34. This gear case incloses, or partly incloses, the gear 33 and rotates thereabout, and as it rotates about the gear a pinion 35, located on a shaft 36 extending through the case, is caused to 15 rotate by engaging with the gear 33. This shaft 36 connects with the member 26 so that when the pinion 35 and shaft 36 rotate, due to the rotation of the case about the gear, the log or work piece will rotate, and also revolve 20 about the axis of the cutter.

Extending from the shaft 36 is a link 37, one end of which is attached to the shaft 36 by means of a strap 38, while the other end is attached to the free end of a crank 39 located on the upper end of a shaft 40, which is operated by the driving gear 17. The upper end of shaft 40 is supported by means of a bracket 41, which extends from the lower ends of two adjacent carriages 28. The shaft 40 is supported loosely on the bracket 41 so that as the crosshead moves downwardly the bracket will slide along the shaft 40. The veneer strip as it is cut from the wood or log is indicated by the numeral 42 and is received on the carrier 9, from which it may be discharged in any suitable manner.

In Figure 2 a piece of timber, such as a pole or log, is shown in a tilted or inclined position with its lower end supported in a cone-shaped cutter. The cutter is stationary. The log is inclined to the axis of the cutter and also to the wall of the cutter so that as the log gyrates all parts of the lower end 45 will be cut. The log is caused to rotate and revolve around the axis of the cutter, and the axis of the gear 33 by means of the motor, through the gear 17, shaft 40, crank 39 and link 37.

50 This link acts as a pitman which causes the rotation of the case 34. As the case 34 rotates the pinion is caused to rotate and carry with it the shaft 36, which is rigid with the pinion. This shaft causes the log to rotate. The rotation of the case causes the log to revolve about the axis of the gear so that the log has a rotating and swinging movement. As the log or work piece is cut the weight 31 causes the head to press the log against the cutter, thereby continuously feeding the log from which the veneer is cut.

It will be understood that I desire to comprehend within my invention such modifications as come within the scope of my claims and my invention.

Having thus fully described my invention, what I claim as new and desire to secure by Letters Patent, is:

1. In a method of cutting veneer, holding a cone guide stationary with its axis in a vertical plane, causing a work piece having a conical end to travel bodily about said axis at an angle thereto, the axis of said conical end coinciding with the axis of the guide, and simultaneously rotating said work piece on its own axis and cutting a veneer strip from the conical end of said work piece by a cutting means lying in the face of said cone. 75

2. In a method of cutting veneer, guiding a work piece having a conical end so that the axis of said work piece describes a cone about a central axis, the latter coinciding with the axis of the conical end of the work piece, rotating said work piece about its own axis during the movement, and cutting a veneer strip from the surface of said work piece by locating a cutter in the plane of its conical rotation. 80

3. In a veneer machine, a stationary inclined cutter blade, means for supporting and holding one end of a log from which veneer is to be cut against the cutter blade, and means for supporting the other end of the log and causing it to gyrate. 90

4. In a veneer machine, a stationary inclined cutter blade, means for supporting and holding one end of a log from which veneer is to be cut against the cutter blade, means for supporting the other end of the log and causing it to gyrate, and means to cause the log to move endwise against the blade. 100

5. In a veneer machine, a stationary conical cutter adapted to support one end of a log from which veneer is to be cut, means to support and gyrate the other end of the log, and means to press the log longitudinally into the conical cutter. 105

6. In a veneer machine, a stationary conical cutter having a vertical axis and adapted to support one end of a work piece, and means to support the other end of the work piece and gyrate it around the axis of the cutter and at an angle to the side of the cutter. 110

7. In a veneer machine, a stationary conical cutter having a vertical axis and adapted to support one end of a work piece, means to support the other end of the work piece and gyrate it around the axis of the cutter and at an angle to the side of the cutter, and means to press the work piece against the cutter. 115

8. In a veneer machine, a frame, a stationary conical cutter having a vertical axis and adapted to support one end of a work piece, a head member loosely mounted on the frame, means on the head member to support the other end of the work piece and gyrate it around the axis of the cutter and at an angle to the side of the cutter, and means 125

130

acting on the head to press the work piece against the cutter.

9. In a veneer machine, a frame, a stationary conical cutter having an axis and adapted to support one end of a work piece, a head member slidably supported by said frame in line with the axis of the cutter, means rotatably mounted on the head member for supporting the other end of said work piece, and means for causing the last-named means to rotate and revolve around the cutter axis, whereby the other end of the work piece gyrates.

10. In a veneer machine, a frame, a stationary cutter comprising an inclined blade supported by said frame, a head member supported by said frame above the blade for movement to and from the blade, a gear fixed to said head having its axis in line with the remote end of the blade, a casing rotatably supported about the axis of said gear, a pinion rotatably mounted in said casing in mesh with the gear, means connected to said pinion for engaging one end of a work piece while the other end is supported by the lower end of the blade, and means for rotating the casing, whereby the first-named end of the work piece will rotate and revolve about the axis of the gear.

11. In a veneer machine, a frame, a stationary conical cutter having an axis and adapted to support one end of a work piece, a head member slidably supported by said frame, a gear having an axis in line with the cutter axis fixed to said head member, a casing rotatably supported about the axis of the gear, a pinion rotatably mounted in said casing in mesh with the gear, means connected to said pinion for engaging the other end of the work piece to rotate when the pinion rotates, and means to cause the casing to rotate about the gear axis, whereby the pinion will rotate and revolve about the axes.

12. In a veneer machine, a frame, a stationary conical cutter having an axis and adapted to support one end of a work piece, a head member slidably supported by said frame, a gear having an axis in line with the cutter axis fixed to said head member, a casing rotatably supported about the axis of the gear, a pinion rotatably mounted in said casing and in mesh with the gear, means connected to the pinion for engaging the other end of the work piece to rotate about the gear axis, whereby the pinion will rotate and revolve about the axes, and means operating on the head member to press the work against the cutter.

60 In testimony whereof, I affix my signature.
ROBERT N. HARTZELL.
